US00D930029S

(12) **United States Design Patent** (10) **Patent No.:** **US D930,029 S**
Balles et al. (45) **Date of Patent:** **** Sep. 7, 2021**

(54) **DISPLAY SCREEN OR PORTION THEREOF WITH GRAPHICAL USER INTERFACE**

(71) Applicant: **Apple Inc.**, Cupertino, CA (US)

(72) Inventors: **Scott Balles**, Brooklyn, NY (US); **Gary Butcher**, Los Gatos, CA (US); **Imran Chaudhri**, San Francisco, CA (US); **Jonathan P. Ive**, San Francisco, CA (US); **Ernest Rowe**, San Jose, CA (US); **Alessandro Francesco Sabatelli**, San Francisco, CA (US); **Eric Lance Wilson**, San Jose, CA (US)

(73) Assignee: **Apple Inc.**, Cupertino, CA (US)

(**) Term: **15 Years**

(21) Appl. No.: **29/758,148**

(22) Filed: **Nov. 12, 2020**

Related U.S. Application Data

(63) Continuation of application No. 29/730,548, filed on Apr. 6, 2020, now Pat. No. Des. 914,729, which is a continuation of application No. 29/697,372, filed on Jul. 8, 2019, now Pat. No. Des. 880,525, which is a continuation of application No. 29/675,929, filed on Jan. 7, 2019, now Pat. No. Des. 853,443, which is a continuation of application No. 29/644,207, filed on Apr. 16, 2018, now Pat. No. Des. 837,829, which is a continuation of application No. 29/576,400, filed on Sep. 2, 2016, now Pat. No. Des. 815,651, which is a continuation of application No. 29/541,032, filed on Sep. 30, 2015, now Pat. No. Des. 765,679, which is a continuation of application No. 29/538,921, filed on (Continued)

(57) **CLAIM**

The ornamental design for a display screen or portion thereof with graphical user interface, as shown and described.

DESCRIPTION

FIG. 1 is a front view of a display screen or portion thereof with graphical user interface showing the claimed design; FIG. 2 is a second embodiment thereof; FIG. 3 is a third embodiment thereof; FIG. 4 is a fourth embodiment thereof; FIG. 5 is a fifth embodiment thereof; FIG. 6 is a sixth embodiment thereof; and, FIG. 7 is a seventh embodiment thereof. The broken lines in the figures show a display screen or portion thereof, and form no part of the claimed design.

1 Claim, 2 Drawing Sheets

Related U.S. Application Data

Sep. 9, 2015, now Pat. No. Des. 762,701, which is a continuation of application No. 29/457,353, filed on Jun. 9, 2013, now Pat. No. Des. 738,889.
